Geo. H. Parmelee,
his ATTORNEY.

UNITED STATES PATENT OFFICE.

HENRY B. NICHOLS, OF PHILADELPHIA, PENNSYLVANIA.

DEVICE FOR USE IN THE MANUFACTURE OF RAIL-JOINTS.

No. 826,528.

Specification of Letters Patent.

Patented July 17, 1906.

Application filed July 18, 1904. Serial No. 217,985.

To all whom it may concern:

Be it known that I, HENRY B. NICHOLS, of Philadelphia, in the county of Philadelphia and State of Pennsylvania, have invented a new and useful Improvement in Devices for Use in the Manufacture of Rail-Joints, of which the following is a full, clear, and exact description, reference being had to the accompanying drawings, which form a part of this specification.

My invention has relation to devices for use in the manufacture of railway-rail joints of the type described and claimed in Patents Nos. 673,829, 717,025, and Reissue No. 12,074, and is designed to provide means of simple, convenient, and efficient character by means of which the molten spelter or other filling material may be introduced under the heads of the jointed rails.

With this object in view my invention consists in a device forming a combined pouring gate and dam of the novel construction, arrangement, and combination of parts, all substantially as hereinafter described, and pointed out in the appended claims, reference being had to the accompanying drawings, in which—

Figure 1 is a plan view of a rail-joint with the devices embodying my invention applied thereto; Fig. 2, a perspective view of one of the said devices, and Fig. 3 a section on the line 33 of Fig. 1.

The numerals 1 1 designate the jointed rails, and 2 2 the joint-plates, which in accordance with the above-noted patents are so shaped and applied as to leave spaces 3 between their upper flanged ends 2^a and the under sides of the heads and trams of the rails for the reception of a filling material introduced in a molten state. These spaces 3 being laterally open throughout their length and the openings thereof being underneath the heads and trams of the rails, some difficulty would be experienced in properly filling them with molten material without undue waste without the use of devices such as are provided by my invention. These devices consist each of an elongated damming-piece provided with supporting-hooks 4 for engagement with the heads or tram of the rails, a vertical flange portion 5, which bears against the edges of the rail trams or heads, a step or shoulder portion 6, which bears against the edge of the flange 2^a of the joint-plate, and a lip 7, which extends underneath the said flange 2^a. In the flange portion 5

are formed a number of recesses 8, which serve as sprues or gates to conduct the molten material into the opening 3. The portions 6 and 7 of the device are covered with asbestos cloth 9 or other refractory material, which effectually closes the openings around the space to be filled and prevents the escape of the molten metal. This covering is shown partially removed in Fig. 2. The different parts of the device are removably secured to each other by means of bolts 10, and the covering is clamped between the parts. It can therefore be readily renewed at any time. When engaged with the rail in the manner shown, said devices are self-supporting; but they are preferably each provided with a handle 11 for convenience in moving them from place to place. The devices used at the two sides of the joint are substantially duplicates of each other, except as to the exact form of the portions 6 and 7, which are shorter on the devices used at the head side of the rails. The particular shape of these portions will necessarily vary in this device with the particular section of rail with which it is to be used. With a guarded or grooved tram-rail these parts are shaped to fit against and underneath the outer surface of the guard or groove flange.

In operation the devices are engaged with the rails at the joints in the manner shown in Figs. 1 and 3. The ends of the spaces 3 are closed with clay or other suitable dams, and the molten spelter is then poured from ladles into the sprues or gates 8. The devices are then removed and applied to another joint.

By means of these devices the joints may be quickly and easily poured with a minimum waste of the molten metal.

I do not wish to be limited to the exact construction and arrangement which I have herein shown and described, as changes may be made in the details thereof without departing from the spirit and scope of my invention.

Having thus described my invention, what I claim as new, and desire to secure by Letters Patent, is—

1. The herein-described device for use in the manufacture of rail-joints, and consisting of an elongated portion arranged to extend under the head or flange of a rail and meet and abut the upper portion of a joint-plate, a damming piece or flange at the outer edge of said portion, and means for supporting the device on the rails.

2. A device for use in the manufacture of railway-rail joints, consisting of an elongated damming-piece provided with a yielding covering of refractory material, and formed with one or more pouring gates or sprues, and means for supporting said piece on the jointed rails.
3. A device for use in the manufacture of rail-joints, consisting of a vertical flange portion formed with rail-engaging hooks, and with one or more pouring gates or sprues, a step or shoulder portion, and an extending lip portion.
4. A device for use in the manufacture of rail-joints, consisting of a vertical flange portion formed with rail-engaging hooks, and with one or more pouring gates or sprues, and a step or shoulder portion, means for de-
- tachably securing said portions to each other, and a refractory yielding covering secured between said portions.
5. The herein-described device for use in the manufacture of rail-joints, comprising an elongated damming-piece arranged to extend under the head or flange of a rail and meet and abut the upper portion of a joint-plate, and formed with one or more pouring gates or sprues, and supporting arms or hooks secured to the said damming-piece and adapted to engage the rails.

In testimony whereof I have affixed my signature in presence of two witnesses.

HENRY B. NICHOLS.
